UNITED STATES PATENT OFFICE

2,489,690

STEAM GENERATOR

Joseph W. Wallin, Williamsport, Pa., assignor to
 E. Keeler Company, Williamsport, Pa., a corporation of Pennsylvania

Application September 26, 1944, Serial No. 555,771

2 Claims. (Cl. 122—347)

1

This invention relates to improvements in steam generators of the type set forth in United States Patent No. 2,097,268, granted to Simon C. Best on October 26, 1937.

The primary object of this invention resides in a steam generator embodying the broad principles of steam generators set forth in the aforesaid patent in which two connected steam generating units are arranged in a single setting and fired by a single furnace. By such an arrangement, it is possible to provide a relatively large steam generating unit over a single furnace in a minimum space and obtain a greater water storage and steam liberating area.

Another important feature of the invention is to provide a twin unit steam generator in which the units are interconnected in a novel manner for operation as a single steam generator having a common water level.

A further feature of the invention is the provision of a steam generator embodying twin steam generating units superimposed over a furnace or combustion chamber, the whole or part of which is enclosed in a single setting constructed of either all refractory material, or a combination of refractory material, insulating material, and an outer steel jacket or casing, the refractory materials being partially protected from the heat generated in the furnace or combustion chamber by water wall tubes which constitute an adjunct of the pressure unit.

A further feature of the invention is to provide a twin-unit steam generator which may be installed over a furnace in which either oil, coal, wood, bagasse or other fuel may be used with such modification in the design of the furnace as may be necessary for the various types of fuel burning equipment required for burning the aforementioned fuels.

A still further feature of the invention is the provision of a twin-unit steam generator in which parts of the same are arranged in a novel manner to produce a single compact steam generator unit requiring a minimum amount of installation space, and capable of being economically operated at very high rates of combustion and steam generations without frequent and costly repairs.

Other novel features of the invention will become apparent as the following specification is read in conjunction with the accompanying drawings, in which,

Figure 1 is vertical longitudinal sectional view taken through one of the units of the twin-unit generator, certain parts being illustrated in elevation.

2

Figure 2 is a vertical transverse sectional view on the line 2—2 of Figure 1.

Figure 3 is an enlarged vertical sectional view on the line 3—3 of Figure 1.

Referring to the drawings by reference characters, the numeral 10 designates the twin-unit steam generator in its entirety which broadly includes a pair of side-by-side steam generator units A and B, a forward single furnace or combustion chamber C which is common to both units A and B, and a single setting D which encloses the units A and B and chamber C. The setting D includes a front wall 11, opposed rear wall 12, opposed side walls 13—13, and a roof or

15 top wall 14.

A refractory bridge wall 15 forms the rear wall of the furnace C, said bridge wall rising vertically within the setting and extending transversely thereof. The top of the bridge wall terminates short of the roof 14 to provide a communicating passage 16 between the upper portion of the furnace C and the rear gas flow compartment 17 which constitutes that area within the setting which is rearward of the bridge wall

25 15. A gas and smoke outlet 18 is provided in the rear wall 12.

The furnace C may be fired by either oil, coal, wood, bagasse or other fuel. In the drawings I have shown for illustrative purposes a coal burning installation known as a multiple retort rear dump type of stoker E. Coal to be burned by this type of stoker is fed to a hopper F at the front of the setting, from which it discharges onto the stoker grate surface G which has a

35 series of retorts, at the bottom of each of which there is a pusher bar which oscillates back and forth causing the fuel to move and burn progressively toward the rear of the grate, combustion thereof being completed by the time the rear

40 of the furnace has been reached and where the ashes drop off into a chamber H. The heat from the burning fuel together with the hot gases and smoke therefrom rises in the furnace C, sweeps over the top of the bridge wall 15 and travels

45 in an undulated passage to the gas and smoke outlet 18 as indicated by the arrows in Figure 1. The bottom of the gas flow compartment 17 is provided with soot-hoppers K into which soot

50 drops during travel of the hot gases and smoke through said compartment. The discharge end of each soot-hopper is normally closed by a soot

gate L which may be opened when the soot collected in the hopper is to be emptied therefrom. It will be understood that when fuel other than 55 coal fed to the furnace by stoker is used, the

design of the furnace may be changed accordingly, but in all instances the furnace or combustion chamber C extends the full width of the setting D at the front thereof.

The twin-steam generating units A and B are identical in construction, therefore a description of one will suffice for the other. Each twin unit includes an upper water and steam drum 19 which extends the length of the setting from the front wall to the rear wall thereof. A water inlet pipe 20 extends into the drum 19 through the front end thereof and rising from the top of the drum is a steam outlet 21. The steam outlets 21 of the units A and B are connected by a manifold 22 from which a steam take-off pipe 23 leads (Figure 2).

A lower water drum 24 is mounted at the bottom of the compartment 17 and extends from a point adjacent the bridge wall 15 to and through the rear wall 12. The water drum 24 is in vertical alignment with the upper drum 19. The upper and lower drums 19 and 24 of each of the steam generating units A and B are connected by a bank of boiler-circulating tubes 25 which constitute the primary water heating elements. The outermost tubes of each unit are designated 26 and extend vertically along the refractory side walls 13-13 and act as water wall cooling tubes. The tubes 25 are arranged in spaced transverse rows with the tubes of one row staggered relative to the tubes of the next adjacent row. The bank of tubes 25 substantially fill the gas flow compartment 17, although a space 27a directly rearward of the bridge-wall 15 may be provided for the installation of superheater tubes (not shown). As the hot gases flow through the compartment 17, the tubes 25 forward of the intermediate baffle 19b receive the more intense heat and those rearward of said baffle a lesser degree of heat. Therefore the rear rows of tubes 25 may be termed down-comers 25a and the forward rows may be termed up-comers 25b.

Referring to Figure 3 it will be noted that the innermost of the tubes 25 of the units A and B are in alignment and these innermost tubes are designated 27. Alternate tubes 27 have their lower ends connected to the water drum 24 of unit A with the upper drum 19 of unit B, while the other tubes 27 have their lower ends connected to the lower drum 24 of unit B and their upper ends connected to the upper drum 19 of unit A. Thus the inner tubes 27 of the banks of tubes 25 interconnect the upper drum of one unit with the lower drum of the other unit and vice versa. This interconnecting of the tubes 27 and drums together, with a cross connection of the furnace wall tubes with the upper drums which will be hereafter described, function in a manner to maintain a common water level in the twin-unit steam generator 10 and to produce certain other novel results as herein set forth.

Water wall tube headers 28-28 extend substantially the length of the side walls 13-13 of the setting below the horizontal level of the lower drums 24-24. Water circulating tubes 29 connect the lower drums 24-24 with the respective headers 28-28, portions of said tubes 29 being encased in an insulated section 30 of the side walls 13-13.

Forward of the bridge wall 15, the headers 28-28 are connected to the forward ends of the upper drums 19-19 by right and left sets of furnace water wall tubes 31 and 32 respectively. Each set of furnace water wall tubes is cross

connected with the upper drums 19-19 of the units A and B in a manner now to be described.

The tubes 31 and 32 rise upwardly from the headers 28-28 along the right and left side walls 13-13 respectively of the furnace C. The drum 19 of the unit B being disposed at the right side of the setting D, alternate tubes 31 extend from the right header 28 directly to the upper drum 19 of unit B. The other alternate tubes 31 have their upper portions 33 bent inwardly to extend across the roof of the furnace and are connected to the inner side of the drum 19 of unit A. Likewise, alternate furnace water wall tubes 32 rise upwardly from the left header 28 along the left inner side wall 13 of the setting and directly connect with the upper drum 19 of unit A. The other alternate tubes 32 have their upper portions 34 bent inwardly to extend across the roof of the furnace and are connected to the inner side of the drum 19 of unit B. The alternate bent portions 33 and 34 of the furnace water wall tubes 31 and 32 cross midway of the furnace adjacent the roof thereof, and this feature together with the interconnecting of the primary boiler circulating tubes and upper drums of the units A and B serves to maintain a common water level within the steam generating units.

The refractory bridge wall 15 is cooled by water taken from the lower drums 24-24 and conveyed by water tubes to the upper drums 19-19 of the units A and B. For cooling the bridge wall 15 I provide a transverse water header 35 which extends the width of the setting and which is disposed rearward of the bridge wall adjacent the bottom thereof. Each drum 24 is directly connected to the header 35 by tubes 36, the single header 35 being common to the tubes 36 of both units A and B. Extending from the front of the header 35 at spaced apart distances along the length thereof are two sets of bridge wall water cooling tubes 37 which parallel the bridge wall and the tubes of the two sets have their upper ends respectively connected to the upper drums 19-19. Alternate tubes 37 extend along the front of the bridge wall while the other alternate ones have portions extending through the bridge wall as at 38 (Figures 1 and 2) and paralleling the rear side of the bridge wall.

In practice, assume that the twin steam generating units A and B are charged with water to the proper common level, and that the furnace C is being fired by the stoker or by any other conventional firing methods. The heated gases evolved by combustion within the furnace or combustion chamber C, radiate heat to the side water wall cooling tubes 31 and 32 and to the crossing portions 33 and 34 thereof, the said portions forming the roof of the furnace, all of which induces effective steam generation in the secondary heating elements of the twin steam generating units A and B.

The gases from the furnace C pass therefrom through the passageway 16 and into the gas flow compartment 17 and act upon the primary heating tubes 25 of the twin units A and B. The tubes 25 are arranged in rows, staggered with respect to the general direction of the gas flow from the furnace C to the gas outlet 18. As the gases pass over, around and between the tubes 25 of the twin units on their way to the gas outlet 18, the direction of flow is reversed by the baffles 19a, 19b and 19c, causing cross flow as well as parallel flow, thus obtaining better diffusion of the gases with resulting better heat absorption of

the tubes 25 of the units A and B. The baffles cause the gas flow to travel in an undulant path from the furnace C to the gas outlet 18. The heated gases sweep the bottoms of the upper drums 19-19 of the units A and B and the tops of the lower drums 24-24 thereof, and diminish in temperature as they travel toward the gas outlet 18. It is the heat transferred to the tubes 25 that causes water to rise in the forward up-comer groups 25b. The group of tubes 25b of the units A and B being subjected to the hottest gases, causes the generation of steam therein and a decrease in the density of the water, thereby inducing upward circulation.

The circulation of water in the twin-unit steam generator after being heated in the aforesaid manner is forward through the headers 28-28, up through the secondary heating tubes 31-32 to the upper drums 19-19, upward through the front rows of primary tubes 25b to the upper drums 19-19 and downward through the rear rows of tubes 25a to the lower drums 24-24, back to the headers 28-28 by way of the tubes 29-29. Alternate innermost tubes 27 of the primary tubes 25 of the units A and B connect the upper drum of one unit with the lower drum of the other unit which cross connection of the upper and lower drums of the units A and B acts to maintain a common water level in the circulatory systems of the twin units. The cross connection of the furnace water wall tubes 31-32 with the upper drums 19-19 also aids in maintaining a common water level in the upper drums of the twin units. The cross connection of the primary and secondary tubes with the upper drums of the twin generating units also serves to effect a uniform generation of steam which accumulates evenly in the upper drums 19-19 and which steam is taken off through the outlet pipe 23 which is connected with the two drums 19-19 by the manifold 22. The twin-unit generator 10 produces in effect a double ring-flow circulation of water which is positive and rapid, which increases heat absorption, and which, by cross connection of the twin units, a uniform generation of steam is obtained and a common water level is maintained in the upper drums of the units.

While I have shown and described what I consider to be the preferred embodiment of my invention, I wish it to be understood that such changes in design as come within the scope of the appended claims may be resorted to without departing from the spirit of my invention.

Having described my invention, what I claim as new and desire to secure by Letters Patent is:

1. A steam generator comprising a setting having a single compartment at the front thereof and a gas flow compartment at the rear thereof, a pair of upper water and steam drums extending side by side substantially the whole length

of said setting including both compartments, a pair of lower water drums extending lengthwise within said gas flow compartment only, one under each of the aforesaid drums, and two banks of primary heating tubes disposed side by side in said gas compartment and substantially filling same and directly connecting each upper drum to the lower drum beneath it, the innermost tubes at adjacent sides of said banks being alternately connected to one upper drum and the lower drum under the other upper drum, water wall tube headers within the setting and water tubes connecting said headers with the upper water and steam drums and the lower water drums of said generator.

2. A steam generator comprising a setting having a single furnace compartment at the front thereof and a gas flow compartment at the rear thereof, a pair of upper water and steam drums extending side by side substantially the whole length of said setting including both compartments, a pair of water drums extending lengthwise within said gas flow compartment only, one under each of the aforesaid drums, and two banks of primary heating tubes disposed side by side in said gas compartment and substantially filling same and directly connecting each upper drum to the lower drum beneath it, the innermost tubes at adjacent sides of said banks being alternately connected to one upper drum and the lower drum under the other upper drum, water wall tube headers within the setting, and water tubes connecting said headers with the upper water and steam drums and the lower water drums of said generator, the headers being arranged along the sides of the setting adjacent the bottom thereof and extending substantially the length thereof, said water tubes including separate sets each rising upwardly from one of the respective headers along the adjacent inner side of the furnace compartment, the upper drums being disposed one at each side of the longitudinal center of the setting, each set of water tubes directly connecting a header to the adjacent lower drum on the same side as said header, and the other tubes of said set extending transversely beneath the upper drum adjacent said side and being connected to the upper drum at the other side of the setting.

JOSEPH W. WALLIN.
